COMPARTMENTED PACKAGING TRAY

James Raymond Loney, Cote St. Luc, Quebec, Canada, assignor to Plastic Packaging Products Limited, Montreal, Quebec, Canada

Filed Nov. 27, 1964, Ser. No. 82,817

Term of patent 14 years

(Cl. D58—13)

I claim:

The ornamental design for a compartmented packaging tray, as shown.
